UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

STALL-SIDE CONSTRUCTION.

1,086,812.

Specification of Letters Patent. Patented Feb. 10, 1914.

Application filed March 15, 1912. Serial No. 683,995.

To all whom it may concern:

Be it known that I, HENRY L. FERRIS, a citizen of the United States, residing at Harvard, in the county of McHenry and State of Illinois, have invented a new and useful Improvement in Stall-Side Construction, of which the following is a specification.

My invention relates to certain new and useful improvements in a stall-side construction, and is fully described and explained in the specification and shown in the accompanying drawings, in which—

Figure 1 is a side elevation of my improved construction; Fig. 2 is a section on the line 2 of Fig. 1; Fig. 3 is a section on the line 3 of Fig. 2; Fig. 4 is a section on the line 4 of Fig. 3; Fig. 5 is a side elevation of a modified form of the construction; and Fig. 6 is a horizontal section on the line 6 of Fig. 5.

Referring to the drawings, 8 is a member which is part of or mounted adjacent to a stall-end. The present specific form of member 8 is a casting mounted on a vertical post, the casting serving as means for supporting the stall-ends. However, as far as the present invention is concerned, this construction is wholly immaterial, the only point being that at or near the stall-end there being some member, such as the member 8, to which the end of a chain 9 can be attached.

10 is a post at or near the rear end of the stall to which the opposite end of the chain 9 is attached. The post 10 is so arranged that it can be lowered or removed for the purpose of entirely removing the stall-side. Broadly speaking, this is the present invention.

In barns of modern sanitary construction, it is the custom to arrange to build a cement floor and to arrange the stalls in long rows. For cleaning the stalls it is very desirable that all obstructions be removed and, it may be added, that even when the animals are in the stalls there may be occasions when it is desirable to remove the stall-side after the animal is secured by the stanchion which is, of course, incorporated somewhere in the stall-construction. Three alternative methods of providing for the removal of this post, or its lowering to the floor, are shown. In the form of Figs. 1 to 4 inclusive, a bracket 11 is secured to the floor, the same having upwardly-extending ears 12 between which the post 10 is pivoted. The ears 12 have at

their rear hooks 13, and a loop 14 is pivoted to the post 10 at its lower end and is adapted, when the post is in vertical position, to engage the hooks 13 of the ears 12. Thus, by releasing the loop from engagement with said hooks, the post can be swung down to the position shown in dotted lines, so as to entirely clear away the separating partition between two stalls. This post can be raised and will automatically lock itself in a vertical position in an obvious manner. In the form shown in Figs. 5 and 6, another form of bracket indicated by 15 is used. This bracket is in general similar to the bracket 11 except that the upwardly-extending ears 16 have no hooks and to take the place of the post-locking loop and hooks a chain 16 is attached to the top of the post and is adapted to engage an eye 17 in the floor by means of a snap-hook 18 in an obvious manner and with obvious results.

In barns of modern sanitary construction, it has become the practice recently to build the floors of concrete for ready cleansing and to construct at the rear of the stalls a relatively-deep gutter, such as is shown in the drawings. Such a deep gutter is especially desirable because all the droppings and manure fall therein and the remainder of the barn can be kept quite clean; and this deep gutter can be cleansed very readily by flushing. Such a gutter is, however, almost continuously wet and slippery, and the cows in backing out of the stalls are likely to step in the gutter thereby slipping and straining themselves. Such injuries do not occur either when there is no gutter, or when the cow has an opportunity to turn around and walk across the gutter. The opportunity to turn before leaving the stall is afforded in those stalls where no separating partitions are provided, but in such stalls when one cow lies down the adjacent cows frequently step upon it so as to injure it, the udder of the cow being peculiarly liable to injuries of this character. Thus it will be seen that the presence of the deep gutter renders the cows liable to injury of one character, which it has been heretofore possible to prevent only by laying them open to injuries of another character. That is, if the injuries due to the deep gutter are to be prevented, the practice has heretofore been to use no partitions, so that the cows are liable to injury by each other. In the

present form of construction, however, the deep gutter is used and the partitions are made readily removable. The first cow in the series is milked, the chain forming the adjacent stall is then released and the cow walks out sidewise without having to back across the gutter. The next cow is then milked and released in a similar manner, and so on, until all have left the barn, the series of stalls is then laid clear for easy cleaning and before the cows return all the stall-sides are replaced in their normal positions and the cows return in the usual way, but in entering the stalls they walk in head first so that the gutter is in clear view and there is no danger of their stepping therein and straining themselves as when they back out.

I am aware that removable stall-sides have been used in cattle-cars, but they have been used there for a wholly different purpose. Such cars have no gutters at the rear, nor, in fact, any space behind the position which the cows occupy in which they can pass in and out and the partitions are made removable, not for the purpose of permitting the cow to avoid passing over the gutter in leaving, but so that the cows may have access to the end compartments. There is in the present construction, therefore, a novel interaction between the gutter at the rear and the removable partition at the side, the gutter introducing a danger of injury, which the removability of the partition alone removes.

I realize that considerable variation is possible in the construction here shown and described, and I do not intend to limit my-

self to the form here shown, except as pointed out in the claims, as it is my intention to claim all the novelty inherent as broadly as is permissible in view of the state of the art.

I claim as new and desire to secure by Letters Patent—

1. In a stall-construction a post pivoted adjacent to the rear of the stall to be swung downward, and a flexible member extending therefrom to the front of the stall, for the purpose set forth.

2. In a stall-construction a post pivotally supported adjacent to the rear of the stall adapted to be swung down, a flexible member running therefrom along the side of the stall to the front end thereof, and means for maintaining the post in vertical position.

3. In combination a bracket adjacent to the rear of the stall, a post pivoted therein, mutually-engaging loop and hooks on the post and bracket to lock and release the post, and a flexible member running from the post to the front of the stall, for the purpose set forth.

4. In a stall-construction a post pivoted adjacent to the rear of the stall to be swung downward, and a member extending therefrom to the front of the stall, for the purpose set forth.

In testimony whereof I have hereunto set my hand this 11th day of March, 1912.

HENRY L. FERRIS.
